UNITED STATES PATENT OFFICE.

JOHN F. O'CONNOR, OF CHICAGO, ILLINOIS, ASSIGNOR TO WILLIAM H. MINER, OF CHAZY, NEW YORK.

ROLLER SIDE BEARING.

1,290,322.

Specification of Letters Patent.

Patented Jan. 7, 1919.

Application filed February 16, 1918. Serial No. 217,514.

To all whom it may concern:

Be it known that I, JOHN F. O'CONNOR, a citizen of the United States, residing at Chicago, in the county of Cook and State 5 of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

In the operation and construction of railway cars, it is customary to employ anti-friction roller side bearings between the 15 ends of the body and truck bolsters to thereby minimize the friction when the trucks swivel with respect to the car body and also to prevent undue swaying of the car body 20 relatively to the trucks. In many instances, it has been found advisable to render these anti-friction roller side bearings adjustable in such a way as to always insure a true line 25 contact between the anti-friction rollers and the opposed engaging surfaces. The general practice to accomplish the last named 30 object has been to employ a rockably mounted cradle to carry the anti-friction roller so that the anti-friction roller could oscillate or swing as an entirety about an axis 35 transverse to the axis of rotation of the 40 roller.

One object of my invention is to provide an anti-friction roller side bearing, which 35 will accomplish the same results as are accomplished by those structures employing a rockably mounted cradle for carrying the anti-friction roller and which at the same time will avoid the necessity of using the 40 cradle or any extra member corresponding thereto.

Another and more specific object of the invention is to provide an anti-friction roller side bearing, more particularly adapted for 45 railway cars wherein the anti-friction roller is adjustable to compensate for variations in the angle between the opposed bearing surfaces of the bolsters and wherein the side bearing comprises merely the anti-friction 50 roller and the single retaining member for supporting it.

In the drawing forming a part of this specification, Figure 1 is a vertical, sectional view, taken through the end portions of a 55 body and truck bolster showing my im-

proved side bearing in connection therewith. And Fig. 2 is a sectional view, taken substantially on the line 2-2 of Fig. 1.

In said drawing, 10 denotes the upper portion of a truck bolster to which the improved side bearing is adapted to be secured, and 11 denotes the under portion of an opposed body bolster, it being understood that the two bolsters are pivotally connected at their centers in the usual manner.

The improved side bearing, as shown, comprises a base or retaining casting A and an anti-friction roller B.

The base casting A is shown as of hollow, substantially rectangular form with end 70 walls 12-12, side walls 13-13 and base flanges 14-14 by which it is adapted to be riveted to the body bolster. Each of the side walls 13 is provided with a hollow laterally extended cup-shaped enlargement 15 75 suitably braced as by a flange 16, said cup-shaped enlargement on its inner side being of substantially conical form except that the surface is curved on the arc of a circle, as indicated at 17, when any section is taken 80 therethrough.

The roller B is of cylindrical form with its upper surface extending above the top of the base casting A and at each side thereof, the roller B is provided with preferably integral 85 laterally extended trunnions 18-18, said trunnions 18 being also of substantially conical form with the exception that the surfaces thereof are also curved, as indicated at 19, on radii corresponding to the radius of 90 curvature of the interior surfaces 17 of the bearings provided in the casting A. As clearly shown in Fig. 2, the trunnions 18 do not fully occupy the space provided therefor in the bearings of the base casting, but on 95 the contrary, clearance is left between the ends of the trunnions and the opposed end walls of the bearings sufficient to permit the roller B as an entirety to oscillate or adjust itself about an axis perpendicular to the 100 axis of rotation of the roller B. The upper walls of the bearings in the base casting are suitably cut away, as indicated at 20, to permit the roller with its trunnions to be dropped into place, and it will be noted also 105 that the width of the roller is less than the space between the side walls of the base casting so as to permit the oscillatory movements of the roller B, hereinbefore mentioned.

In operation, it is apparent that the roller 110

B is free to rotate about its axis and at the same time should the bearing surface 21 thereabove assume a position at an angle to the upper surface of the opposed truck 5 bolster, the pressure on the roller B will automatically cause the latter to adjust itself in the conical bearings provided therefor about an axis perpendicular to the axis of rotation of the roller. By employing the 10 curved bearing surfaces, hereinbefore described, it is evident that a true surface bearing contact will always be maintained between the trunnions and the bearings therefor regardless of the position taken by the 15 roller B. The roller side bearing accomplishes the results obtained by those former devices wherein the roller has been mounted in a separate rocking cradle, and obviously at a much less expense inasmuch as the cradle and the expense incident thereto are done 20 away with.

Although I have herein shown and described what I now consider the preferred manner of carrying out the invention, the 25 same is merely illustrative and I contemplate all changes and modifications that come within the scope of the claims appended hereto.

I claim:

30 1. In a roller bearing, the combination with a retaining and supporting member, of a roller mounted in said member and having laterally extended trunnions, said member being provided with bearings for said

trunnions, said trunnions and bearings being both curved lengthwise thereof to thereby permit the roller and said trunnions to oscillate as a unit about an axis perpendicular to the axis of rotation of the roller. 35

2. In a roller bearing, the combination 40 with a hollow retaining casting having spaced side walls, said side walls being provided with hollow bearings curved lengthwise thereof, of an anti-friction roller having laterally extended trunnions, said trunnions being curved lengthwise thereof to correspond with the curvature of said bearings, there being clearance between the ends of said trunnions and the ends of said bearings to thereby permit said trunnions to 45 shift endwise within said bearings.

3. In a roller bearing, the combination 50 with a hollow retaining casting having spaced side walls, said side walls being provided with hollow bearings curved lengthwise thereof, of an anti-friction roller having laterally extended trunnions, said trunnions being curved lengthwise thereof to correspond with the curvature of said bearings, there being clearance between the ends of 55 said trunnions and the ends of said bearings to thereby permit said trunnions to shift endwise within said bearings, said trunnions being formed integrally with the roller.

In witness that I claim the foregoing I 60 have hereunto subscribed my name this 7th day of Feb., 1918.

JOHN F. O'CONNOR.
